UNITED STATES PATENT OFFICE.

WILLIAM KILIAN, OF CINCINNATI, OHIO.

DESIGN FOR A METAL DISH.

No. 39,052.

Specification for Design.

Patented Feb. 4, 1908.

Application filed July 29, 1907. Serial No. 386,172. Term of patent 7 years.

To all whom it may concern:

Be it known that I, WILLIAM KILIAN, citizen of the United States, residing at Cincinnati, in the county of Hamilton and State of Ohio, have invented a new, original, and ornamental Design for Metal Dishes, of which the following is a specification, reference being had to the accompanying drawings, forming a part thereof.

The figure is a plan view of a metal dish, showing my new design.

I claim:

The ornamental design for a metal dish, as shown.

WILLIAM KILIAN.
